FLORAL BASKET

Howard M. Petter, Youngstown, Ohio

Application April 23, 1931, Serial No. 532,272

11 Claims. (Cl. 47—41)

My invention is a floral container.

The main purpose of my device is a waterproof container and basket structure which is peculiarly adapted to the deposit therein of flowers and plants, and conserving a very decorative effect between the container itself and the floral contents.

A major object is the construction of such a device as lends itself to many variant decorative features.

A further object is the method of construction whereby the handle portions lock the container portion to a base and preserve the integrity of the receptacle feature without attaching the same to the base.

Another object is the method of construction of the receptacle portion and the method of handle construction in coactive relation to the receptacle and the base.

20 The attached drawings show an embodiment of my device wherein Fig. 1 is an elevation of the primary container.

Fig. 2 is a container with a base attached.

Fig. 3 is an elevation of the device in the form 25 of a complete basket having the container upon a base, and a handle which is part of the means for attaching the container to the base.

Fig. 4 is a vertical section showing the relation of the parts with the handle forming members in primary position.

Fig. 5 is a cross section of the container at 30 5—5 of Fig. 4.

Fig. 6 is a sectional view of the device as shown in Fig. 4 but showing the inceptional crossing 35 of the handle forming members prior to their being twisted one around the other.

Fig. 7 shows a method of fixing the flexible attaching members to the base.

Fig. 8 shows the method of attaching the ends 40 of the flexible members forming the handle, and constricting the said members to give tension to the point of contact with the container.

Fig. 9 is a modified form of the device, used as a flower box.

45 As illustrated the device consists of a receptacle which said receptacle is formed out of a single sheet of waterproof material, preferably a sheet of pliant metal; the central portion of the said waterproof sheet forms a bottom 10 from 50 which the vessel walls 11 are drawn up into corrugations consisting of crinkles 12 and recesses 13 to form a sinuous contour circumferentially. It will be observed that the corrugations in the side walls are deepest at the top, and run out to nothing 55 at the bottom. The shape of the sheet from

which the vessel walls 11 are drawn up is not limited to any specific contour but can be varied in accordance with any desire so as to vary the elevation of different parts of the rim 14. The said receptacle may be used for the insertion of a 60 pot containing a plant, but the primary purpose is the assemblage therein of floral articles composing a floral display; and the peculiar virtue of this corrugating of the walls 11 of the receptacle is that the various crinkles 12 tend to give 65 fixed position and location to those elements of the floral assemblage which are primarily designed to be frontally displayed, and are directly operative in maintaining the position of the 70 entirety of the floral articles inserted in such receptacle 10 and intended to be displayed thereby. The crinkles 12 and the recesses 13 subserve this 75 very desirable result wholly in addition to the peculiar ornamental character of the vessel itself.

In Fig. 3 I show the receptacle 10 in relation to an ornamental base 15: this said base 15 has in it a plurality of holes 16—at least two of the same—one on either side of the base 15, as related to the receptacle 10. Into these holes 16 are inserted ends of flexible rods 17,—such as reeds—and which are fixedly attached to the base 15 by a nail 19 driven through a portion of the base and through the inserted portion of the flexible rods 17; but the said flexible rods may be held permanently in the base by some other 80 normal method: the principle here being that the flexible rods 17 so inserted shall be permanently therein imbedded.

The flexible members 17 attached thus to the base 15 are designed to be placed so adjacent to the walls 11 of the receptacle 10 that they will 85 position the receptacle 10 centrally on the base 15; and each said flexible attaching device 17 is somewhat resiliently placed in one of the recesses 13 of the crinkled walls 12 to a point practically adjacent the rim 14 of the receptacle. Adjacent to the rim 14 of the receptacle the flexible attaching member 17 is pinched into connection with the wall of the container by some 90 means, such as what may be called a hog-ring, as shown at 20 in Figs. 4, 5, and 6. Although I prefer to use a block of wood for the base 15 the same may be of any material which will form a 95 decorative supporting base of desirable character.

100 In various figures of the drawings I show a loop handle in combination with the receptacle 10 and base 15, forming a floral basket. This handle comprises the flexible members 17, which 105 not only fixedly attach the container 10 to the 110

base 15, but also by continuation into a bow or loop over the receptacle constitute a handle for transporting the said device as a unit. I preferably perforate the base 15 with four holes 16 5 so positioned in the base 15 that there will be practically an even distribution of the said holes 16 to provide that the receptacle will be seated within the circuit of said holes and be normally positioned thereby on the base 15. In using four 10 of said holes with the corresponding flexible members 17 I prefer to place two flexible members 17 on either side of the receptacle 10 in crinkled channels somewhat adjacent each other on either side, as shown in Fig. 4. After placing the said 15 flexible members 17 in such position on either side I pin them to the receptacle as shown in Figs. 4, 5, and 6 with attaching devices 20. The flexible members 17 are then twisted as shown in Fig. 4 creating a primary tension upon the walls 20 of the receptacle 10, and then the same are drawn across each other as shown in Fig. 6, at 26 the free ends of each pair of flexible members 17 being twisted around the other pair and brought to an attaching point somewhat near where the 25 flexible members 17 are in contact with the rim 14 of the receptacle. At the point where the ends of the twisted members 22 and 23 terminate a constricting device 25 is applied which serves to fix the ends of the flexible members and at the 30 same time draw the individual members 22 and 23 of each pair of flexible members together, thus increasing the locking tension of the flexible members 17 upon the channel walls of the crinkled body of the receptacle.

35 I show a modified form of the device in Fig. 9, which is designed to provide a species of flower box. The means of attaching the waterproof receptacle at either end to the base 15 is a flexible member 24 in the form of a staple; its prongs 40 being inserted in the holes 16 of the base 15, the bent portions extending up above the rim 14 to act as handles; the said staple resting in the recesses 13 and being fixedly associated with the walls 11 by the clips 20.

45 It will be readily observable that the receptacle 10 can be formed out of any shaped sheet of waterproof material and give to the rim 14 any contour desired for practical or ornamental purposes. The device makes unusual provision for 50 the assemblage of a bouquet, or combination of flowers, or floral decorations; by reason of the fact that the stems of plants, leaves and foliage will automatically drop into these crinkles and remain positioned and provide a holding for a central mass background: the crinkles and wrinkles can be so formed that they will automatically position anything placed therein. The device is also peculiarly adapted to the assemblage 55 therein of growing plants and even the deposit 60 therein of a potted plant. It will be readily observable that the receptacle portion is subject to the most artistic decorative treatment: and in the basket formation the handle can be treated artistically, in harmony with the receptacle and base, offering a heretofore unknown 65 opportunity.

I do not limit myself to the device as shown except insofar as I am limited by the scope of my claims.

70 I claim—

1. In a floral pot the combination of a base having vertical apertures therein; flexible handle members having terminals anchored in the apertures in said base, a receptacle formed from a 75 single piece of pliant metal drawn up into a ves-

sel form assembled on said base and confined by said handle members, the drawn up portions of said receptacle being crimped into crinkles flaring upwardly and outwardly, sinuous in their circular contour; the handle members being so positioned that the metal receptacle is seated lockingly between opposing handle members, said handle members being adapted to align between certain channels of the crinkled receptacle walls and lock the said metal receptacle to the base, means adjacent the rim of the receptacle for gripping the handle members to the metal receptacle, the handle being formed by twisting the handle members upon each other inducing a resiliency in the handle portion and causing the same to coact with the metal receptacle.

2. A floral basket comprising a base member, a receptacle mounted thereon formed from a single sheet of pliant metal the said single sheet of pliant metal having a base portion at the center thereof and outwardly flaring sides drawn upward from the said base, said sides being corrugated with the corrugations running in an up and down direction, the said corrugations providing channels for fixedly positioning floral elements assembled in said receptacle; handle members having terminal portions fixedly attached to the base member and portions thereof seated in recesses of selected corrugation channels; attaching means securing together the handle members and the corrugated walls of the receptacle whereby to lockingly attach the receptacle to the base and provide handle portions for transportation.

3. In a floral basket the combination of a metal basket member and a handle formed of reeds; the said basket member being formed out of a single sheet of pliant metal, there being a central base portion and walls drawn up therefrom, the said walls being crinkled into sinuous flaring vertical channels; the reeds forming the handle having portions thereof lying in recesses of the channelled walls and fixedly attached to the metal basket member by gripping means spaced from the rim of the metal member.

4. In a floral container, a base having spaced apertures therethrough, a receptacle mounted upon said base between said apertures, said receptacle being formed of sheet metal and having deeply corrugated side walls, the corrugations of which are adapted to hold and support flower stems, and a handle formed as a loop, the ends of the handle being secured in said apertures and the lower portions extending into opposite corrugations of the receptacle wall.

5. In a floral container, a base having spaced apertures therethrough, a receptacle mounted upon said base between said apertures, said receptacle being formed of sheet metal and having deeply corrugated side walls, the corrugations of which are adapted to hold and support flower stems, a handle formed as a loop, the ends of the handle being secured in said apertures and the lower portions extending into opposite corrugations of the receptacle wall, and handle engaging members mounted upon the receptacle extending across said opposite corrugations outside the handle elements.

6. In a floral container, a base, a loop handle, the ends of said handle being secured to the base in spaced relation, a receptacle formed from a single piece of sheet metal shaped up into a vessel form, the shaped up portions being corrugated in an up and down direction, said receptacle being mounted upon the base with opposite cor-

fugations embracing the lower portions of the loop handle, and means for securing the receptacle and handle against relative movement.

7. In a floral container, a base, a loop handle, 5 the ends of said handle being secured to the base in spaced relation, a receptacle formed from a single piece of sheet metal shaped up into a vessel form, the shaped up portions being corrugated in an up and down direction, and the corrugations running out at the bottom of the receptacle, 10 said receptacle being mounted upon the base with opposite corrugations embracing the lower portions of the loop handle, the bottom of the receptacle fitting snugly between the ends of the handle 15 at their junction with the base, and means for attaching the handle to the said opposite corrugations.

8. In a floral container, a non-metallic base, 20 said base having spaced apertures formed therein at right angles to the surface of the base, a receptacle mounted upon said base, said receptacle having side walls flared outwardly from the bottom thereof, and the bottom being of a width approximately the same as the distance between 25 said apertures, and a loop handle of resilient material, the ends of which fit snugly within said apertures and are anchored therein, whereby the lower portions of the handle are resiliently held against the side walls of the receptacle, and means 30 for attaching the handle to the side walls near the upper end of the receptacle.

9. A floral basket comprising a one-piece sheet metal bottom and sides, the sides being flared outwardly and upwardly from the bottom, the side walls being corrugated in an up and down direction, the corrugations running out at the bottom and being relatively deep at the top, whereby the stems of flowers making up a bouquet may be definitely held in selected positions, and a handle attached to the basket within oppositely arranged corrugations. 80

10. In an article of the character described, the combination of a base member, a fluid retaining container having fluted walls and disposed on said base member, a handle having a plurality of strands extending downwardly along side and into the recessed portions of said fluted walls and connecting with said base member, said strands serving to retain said handle, base and container in a cooperative assembled relation. 85

11. A floral container comprising a base, a 90 seamless fluid retaining vessel disposed on said base, said vessel having a flat bottom from which walls with flutes of increasing size rise and terminate irregularly to form serrated edges around the rim of the vessel to present an artistic appearance, and a handle composed of a plurality of entwined strands, certain of said strands extending downwardly into the troughs of said flutes and connecting with said base to hold the base, vessel and handle in assembled relation. 100 105
